UNITED STATES PATENT OFFICE.

ARTHUR ATWATER KENT, OF PHILADELPHIA, PENNSYLVANIA.

CIRCUIT-CONTROLLER.

1,096,109.

Specification of Letters Patent.

Patented May 12, 1914.

Application filed December 22, 1906. Serial No. 349,068.

To all whom it may concern:

Be it known that I, ARTHUR ATWATER KENT, a citizen of the United States, and a resident of Philadelphia, county of Philadelphia, State of Pennsylvania, have invented certain new and useful Improvements in Circuit-Controllers, of which the following is a full, complete, and exact disclosure.

My invention relates to circuit controllers and especially to that class of devices in which a single contact device is used to make and break a plurality of electrical circuits, and my invention is especially applicable for use in connection with internal combustion engines having a plurality of cylinders operating either upon a single drive shaft or a plurality of shafts so connected together as to run synchronously.

The objects of my invention are to employ a positively operated make and break device which will operate in connection with a plurality of circuits and to connect said device with the circuits by means of a distributor or timer in such a manner as to prevent, so far as possible, the sparkings and wear at the points where the circuits are broken, and especially in said distributor.

A further object of my device is to provide a construction in which the spark may be induced either by a positively driven mechanical contact device, which will close the sparking circuit for a uniform definite length of time, irrespective of the speed of the driving mechanism, or by an electro-magnetic vibrator.

Further objects of my invention are to reduce the battery consumption, to effect a more accurate timing of the spark, to produce a constant spark for a plurality of cylinders, to facilitate the starting of the engine, to provide means for testing the spark plugs in the various cylinders, to simplify the construction and reduce the weight of the device, and to simplify the wiring of the sparking system.

Other objects of my invention will appear in the specification and claims below.

In the drawings forming a part of this specification in which the same parts are referred to by like reference characters, Figure 1 is a plan view of my improved mechanical contact device and distributor or timer, the distributor or timer being shown in section; Fig. 2 is a side elevational view of the same, and Fig. 3 is a diagrammatic view of my improved contact device and dis-

tributer as connected up and coöperating with a four cylinder internal combustion engine.

Referring first to the device illustrated in Figs. 1 and 2, 1 indicates a suitable plate or body portion which is provided with lugs 2-3 extending on opposite sides thereof and forming journals for the shaft 4 rotatably mounted therein. The lug 3 is cut away as 60 at 5 to expose the shaft 4 which at this point is provided with ratchet teeth 6. Above the said ratchet teeth 6 is a sliding member 7 provided with a depending or hooked portion 8 adapted to be engaged by 65 the ratchet teeth when the shaft 4 is rotated. This member 7 is supported at its forward end on the upper surface 9 of the cut away portion 5 of the lug 3 and at its rear end by the pin 10 mounted in the cut away portion 70 11 of the projection 12 secured to the base plate 1. This member 7 is held down upon its said bearing 9 and 10 by a rearwardly and downwardly extending tension spring 75 13, which also acts to draw the said member 80 rearwardly so that its rear end normally rests against a stop pin 14 at the rear of the cut away portion 11. The forward end of the 85 said member 7 is also provided with an extension 15 the function of which will appear below. Above the sliding member 7 and loosely pivoted on a stud 16 secured to the base 1 is a block 17 to one side of which is secured a stiff arm 18 the outer end of which is supported on a stud 19 and is 90 bent to form a hook 20 the extremity of which is adjacent the extension 15 of the sliding member 7. To the opposite side of the block 17 a strip of stiff material forming a stop 21 which extends away from said block in a direction substantially parallel to the arm 18 and between said strip 21 and the block 17 is clamped the resilient contact arm 22 carrying at its outer end the platinum contact point 23. This arm 22 consists 95 100 of a strip of flexible and resilient material as of copper or thin spring steel, and it is so sprung, before being assembled in the manner above set forth, that when it is clamped to the block 17 between the same 105 and the stiff stop strip 21 by the screws 24, its free end normally presses against the stop arm 21 with sufficient tension to prevent any oscillation or trembling of the resilient contact arm. The block 17 is retained on the pin 16 by the spring 16' secured to the same and the base plate 1, and 110

it is so positioned as to also hold the arm 18 against the stud 19 and the contact point 23 away from the contact 32 when the end 20 is out of engagement with the extension 15. 5 Secured to the base plate 1 but insulated therefrom by a plate 25 of vulcanite or other suitable insulating material, is an insulated member 26 provided with a projection 27 extending through a suitable opening 28 in 10 the plate 1 and terminating in a spring 29 or other suitable electrical connection by which the bracket 26 may be attached to one of the poles of a suitable source of electrical energy. 30 indicates a similar electrical 15 connection secured to the base plate 1. On the front side of the base plate 1 the said insulated member 26 extends outwardly, adjacent the resilient contact arm 22, and opposite the contact point 23 it is provided with a 20 screw 31 the end of which forms a stationary contact point 32. From the screw 31 to the end of the said insulated member is provided a kerf 33 forming a split nut into which said screw is threaded and a locking screw 34 25 passing through the ends of the said member serves to rigidly clamp the screw 31 in any adjusted position.

To the end of the projection 12 is pivotally mounted a circuit closing key 35, on a 30 pin 36. Said key being provided at one end with a finger piece 37 and having its opposite end, carrying a platinum contact point 38, extending under a projecting and overhanging portion 39 of the insulated member 26. A spring 35¹ tends to hold the point 38 out of contact with the end 39 of the said insulated member 26.

The mechanism above described constitutes a mechanical contact maker or make 40 and break device and when referred to as a whole will be called the contact maker.

Secured to the shaft 4 is a gear 40 meshing with a similar gear 41, mounted on a shaft 42 parallel to the shaft 4 journaled in 45 bearings 43 to the plate 1, the opposite end of said shaft 42 having secured thereto a head 44 adapted to be rotated by said shaft within a circular chamber 45 in the casing 46 rigidly secured to said base plate 1 in any 50 suitable manner. In order to rotate the shafts 4 and 42 synchronously the gears 40 and 41 should be of the same size. The head 44 is provided with a yielding brush or wiper of any suitable description. In the 55 drawings I have illustrated the same as comprising a stem 47 having a head 48 slidably fitted in a suitable opening in the head 44, said stem passing through the diametrical opening 49 and having its opposite end 60 loosely fitted in an alined opening 50 in a screw plug 51.

52 indicates a coiled compression spring surrounding the stem 47 and having its ends in operative engagement with the plug 51 65 and the head 44. By this construction the

head 44 is pressed outwardly by the said spring 52 so that it engages at all times the interior wall of the chamber 49.

Arranged symmetrically around the chamber 45 are stationary contact pieces 53, 54, 55 and 56 insulated from the casing 46 in any suitable manner as by non-conducting sleeves 57. On the said contact pieces are binding posts 58 by which the said contact pieces may be connected to a suitable source of electrical energy, through the primary windings of the induction coils 70 and 75. 75

The device above described constitutes the distributor or timer by which the contact device is put into operative relation with the 80 various circuits to be fully explained below.

59 indicates a suitably located handle or grip by means of which the plate 1 and the various parts mounted thereon, may be rotated about the shaft 4 for the purpose of 85 adjusting or turning the device with the motor with which it may be used.

60, 61, 62, 63 indicate diagrammatically the cylinders of a multiple cylinder, internal combustion engine, each of which has its 90 piston 64 connected by its pitman 65 with the crank 66 on the main shaft 4. The pistons are preferably coupled in complementary pairs, that is to say, one piston is in 95 that position in its cycle when the charge is ready to be exploded while the complementary piston is in that point of the cycle where the exploded gases have been expelled from the cylinder and the cylinder contains an un-explosive mixture. Each cylinder is provided with a jump spark plug 67 shown diagrammatically as having an insulated member 68 and a member 69 grounded to the engine. 100

70 indicates an induction coil one end 71 105 of the secondary winding of which is connected by a wire 72 with the insulated member 68 of the spark plug 67 of cylinder 60, while the other end 73 is connected by wire 74 with the insulated member of the spark 110 plug of complementary cylinder 62. 75 indicates a second induction coil one end 76 of the secondary winding of which is connected by wire 77 with the insulated member 115 of the spark plug of cylinder 61, while its opposite end 78 is connected by wire 79 similarly with the spark plug of cylinder 63.

80, 81, 82 and 83 are keys connected by the wire 84 to the lead 85 which in turn is grounded to the engine through the binding 120 post 86 attached to the cylinder 62. Each of these keys is adapted to contact with one of the terminals of the secondary windings of the induction coils 70 or 75.

One end 87 of the primary winding of the 125 induction coil 70 is connected by the wires 88 and 89 directed with one pole of the battery 90 while the opposite end 91 of the said primary winding is connected through lead 92 contact screw 93, vibrator 94 and lead 95, 130

to wire 96, which is connected by leads 97 and 98 to the opposite contact pieces 53 and 55 respectively of the timer. 99 indicates a switch for shunting the vibrator 94 by having one side connected by wire 100 with the wire 92 and its other side connected to the lead 95 by wire 101. Similarly one end 102 of the primary coil 75 is connected by wires 103 and 89 to the same pole of the battery 90, and the other end 104 is connected through wire 105, contact screw 106, vibrator 107 and lead 108 to wire 109, which terminates in two branches 110 and 111 connected to the opposite contact pieces 56 and 54 respectively.

112 indicates a switch having its opposite sides connected by wires 113 and 114 to the leads 105 and 108 respectively. The opposite pole of the battery 90 is connected by wire 115 to the insulated bracket 26 of the contact maker.

As has been stated above the key 35 is mounted on the plate 1 and when pressed is adapted to contact with the insulated bracket 26.

116 indicates a condenser having one side connected by wire 117 and lead 92 to the end 91 of the primary winding of the induction coil 70 and its other end connected by lead 118 and the wire 115 to the battery 90. 119 is a similar condenser, having one side connected by lead 120 and wire 105 to the end 104 of the primary winding of the coil 75, and its other end connected by wire 121 and wire 115 to the battery 90.

It is to be understood that the shaft 4 is driven from the crank shaft 4' by any suitable gearing (not shown) whereby the ratio of the speed of the two shafts will be constant, and it is to be also understood that although I have shown my contact device and distributor as applied to a four cylinder engine and consequently the ratchet 6 as provided with four teeth and the distributor 45 as provided with four stationary contact pieces, when the device is employed in connection with motors or engines having a different number of cylinders, the corresponding parts of the contact device and 50 timer may be correspondingly varied.

The operation of my device is as follows: By the rotation of the crank shaft 4', the ratchet 6 on shaft 4, is rotated in the direction indicated in the arrow on Figs. 1 and 4, 55 and the downwardly extending end of the slider 7 is drawn forwardly out under the depending end 20 of the stiff arm 18, the slider bearing at all times against the surface 8 and the pin 10, and moving in opposition to the spring 13. When the ratchet has advanced sufficiently far its engaged edge moves downwardly out of engagement with the end 8 of the slider 7, and the spring 60 13 then is free to retract the slider to its original position with its end contacting

with the pin 14. In doing this, however, the depending end 8 rides upwardly over the outer surface 6' of the ratchet teeth 6, and the edge 15 strikes and lifts the stiff arm 18, turning the block 17 on its pivot

70

16 against the action of the spring 16'. The rocking of the block moves the arm 22 and its rigid stop 21 upwardly so that the contact point 23 engages with the stationary contact 32 on the end of the screw 31, thus

75

closing the circuit through the said contact points. The turning of the ratchet 6 in the opposite direction will merely cause the end 8 of the sliding member 7 to move upwardly around the point 14 as a center, and out of

80

contact with the end 20 of the arm 18. This motion of the sliding member will not affect the contact point 23 and the current will not be closed by said contact device. From the above description it will be apparent

85

that while the slider 7 will be advanced at variable speeds depending upon the speed at which the shaft 4 which is connected with the engine rotates upon its return movement it will be always acted upon by the same

90

force, that is to say, by the tension of the spring 13, and therefore, the time between the release of the slider and its return to the position shown in Fig. 1 is always constant. It follows, therefore, that the time

95

of its engagement with the depending end 20 of the arm 18 will also be constant. By the use of my device the time of the closure of the circuit is thus rendered uniform or constant, irrespective of the speed of the

100

engine. Just before the contact points just referred to have been actually closed the brush 48 will have moved into contact with the stationary contact piece 54, thus allowing the contact device to open and close

105

positively the circuit through the induction coil 75 by the following path: battery 90, wire 115 and member 26, stationary contact 32, resilient contact 23, block 17 to plate 1, through the brush 48, grounded to the machine, stationary contact 54, lead 111, wire 109, lead 114, switch 112, lead 113, wire 104, primary winding of induction coil 75, lead 103 and wire 89 back to the battery. This

110

short opening and breaking of the primary circuit will induce a secondary current through the cylinders 61 and 63 as follows: lead 76, wire 77, to the insulated member 68 of the spark plug 67 of the cylinder 61 across the air gap between the said insulated member and the grounded member 69 of the said plug through the frame work of the engine, back to stationary and grounded member 69 of the spark plug 67 of cylinder 63, thence across the air gap and

115

insulated member by lead 79 to the terminal 78 of the secondary coil. So immediately after the brush 48 has moved into contact with the stationary contact piece 53, the contacts 23 and 32 will again be closed and

120

65 contacts 23 and 32 will again be closed and

125

65 contacts 23 and 32 will again be closed and

130

the circuit will be closed through the second primary circuit as follows: battery 90, wire 115, insulated member 26; points 32 and 23, block 17, plate 1, brush 48, contact piece 53, branch 97, wire 96, wire 101 and 100, through switch 99, coil 70, leads 88 and 89 to battery 90; and a secondary current will be induced through terminal 71 of the secondary winding of coil 70, lead 72, plug 67 of cylinder 60, through the ground of the engine to plug 67 of cylinder 62, lead 74 back to terminal 73 of coil 70. Thus it is seen that for every making and breaking of the circuit by means of the contact maker a spark is formed in two complementary cylinders; in one cylinder to explode the charged gases at the end of the compression stroke, and also in the complementary cylinder which contains nothing but spent gases and in which the spark has no effect. It is plain then that before the ratchet wheel makes and breaks the circuit through the points of the contact device, the brush will have moved into contact with a stationary contact of the distributor or timer, and will remain in contact therewith until after the circuit has been again broken to produce a spark in the pair of cylinders 61, 63 and in the pair of cylinders 62, 64 alternately, and since the circuit will not be closed and broken, except when the brush 48 is on a contact in the distributor or timer, there will be no sparking whatever in the distributor. Whenever it is desired the spark may be produced by means of the electro-magnetic vibrators 94 and 107 instead of by the mechanical contact device heretofore described, in which event the switches 99 and 112 would be opened as shown in dotted lines in Fig. 3. Then whenever the key 35 is closed to short circuit the mechanical contact device the electro-magnetic vibrators will rapidly open and close the primary circuits, and induce a sparking current in the secondary circuits as long as the brush 48 is in contact with that stationary contact of the timer or distributor which is connected with its coil, and the rapid succession of impulses set up through its secondary circuit will produce a torrent of sparks in the proper cylinders. This cutting out of the mechanical contact device, and throwing in of the said vibrators to cause the spark is especially useful in starting the engine. Since one cylinder will usually contain an unexploded charge when the engine is stopped, the charge may be exploded without first rotating the cylinders or the shaft upon which the ratchet is mounted by opening the switches 94 and 107 and pressing the key 35 to short circuit the mechanical contact device. It is plain, however, that the same result may be attained by manually closing the contact points 23 and 32, in which case the key 35 might be dispensed with.

Whenever it is desirable to cut out one or more of the cylinders for the purpose of testing whether or not the spark plug is operating correctly, it is merely necessary to press one or more of the keys 80, 81, 82 or 83 to short circuit the corresponding cylinders. Thus, if the key 80 were closed, the impulse in the secondary coil would traverse the wires 78 and 79 to plug 67 in cylinder 63 and thence by the frame work of the machine through the binder post 86 and wire 85, back through key 80 to the terminal 76, thus cutting out entirely the cylinder 61.

I have shown condensers as bridging across from the wire 115 connected to one terminal or pole of the battery 90 to the vibrators in the primary circuit of the induction coil, the position of these condensers being such as to prevent all unnecessary sparking at the points at which the circuit is broken, but it is to be understood that I do not intend to limit my invention to this exact arrangement, since the condensers may be arranged in any manner to bridge across the coil and one or more of the places where the current is made and broken.

It should be stated that when the induction coils are used alone to furnish the impulses to the secondary circuits, the timer itself will act as a make and break device for the primary circuit. It is also apparent that the vibrators 94 and 107 may be prevented from operating while the mechanical contact device is employed to make and break the primary circuit by a variety of means, e. g. by adjusting the screws 93 and 106, so that they contact with their respective vibrators when the same are drawn against the coils, thus dispensing entirely with the switches 99 and 112.

The whole plate which is adapted to be turned or rotated about the shaft 4 by means of the handle 59 and by this means the timing of the spark with respect to the position of the pistons in the cylinders may be adjusted or varied in order to either obtain the best results from the explosions or to vary the speed of the motors.

Having thus described my invention what I claim and desire to protect by Letters Patent of the United States is:—

1. The combination with a pair of electrical circuits, an induction coil in each circuit, and a vibrator operated by each of said coils, of a source of electrical energy, a contact device and means to operate the same, and means to put each of said circuits alternately into series with said source of electrical energy and said contact device before said circuit is closed by said contact device, and to hold the said circuit in series therewith until after the circuit is again broken by said contact device, a condenser bridging said contact device and one of said vibrators, a secondary circuit for each of said

- coils and a pair of sparking plugs in each of said secondary circuits.
2. The combination with a pair of electrical circuits, a source of electrical energy, and an induction coil having a vibrator arranged in each of said circuits, a contact device, a distributer for putting each of said circuits alternately into series with said contact device, a condenser bridging each of said vibrators and said contact device at the point where the circuits are broken by the same, a secondary circuit for each of said coils and a pair of sparking plugs in each of said secondary circuits.
3. The combination with a plurality of induction coils having primary and secondary windings, and each coil being provided with a vibrator to make and break the primary circuit, of a plurality of cylinders arranged in complementary pairs, a sparking plug comprising insulated and grounded members mounted in each cylinder, said insulated members of a pair of plugs arranged in complementary cylinders and arranged in series with the secondary winding of one coil, a contact device, a distributer having movable and stationary terminals, each stationary terminal being arranged in series with the primary windings of one of said coils, an electrical connection from said movable member to said contact device, an electrical connection from said contact device to the other terminal of the primary winding of each coil, and means to operate said contact device and said movable terminal of the distributer synchronously, to produce a sparking impulse in each of the secondary circuits successively.
4. In a sparking system the combination with a mechanically operated contact device for opening and closing a circuit for a constant length of time irrespective of the speed at which said device may be operated, and a distributer, of a plurality of electrical circuits successively thrown into series with said contact device by said distributer, an induction coil in each of said circuits, a pair of sparking plugs arranged in series in each of the secondary circuits of each induction coil, and manual means to ground either end of each of said coils to cut out of the secondary circuit the plug connected to that end of that coil.
5. The combination with a pair of induction coils each having primary and secondary windings, of a contact device having a single circuit closer and breaker, a source of electrical energy and a distributer in said primary circuit, means to operate said distributer to throw said battery and contact device into series with said induction coils alternately and to close said primary circuit through said distributer, a vibrator for each of said coils to make and break the primary circuit, four cylinders of an internal combustion engine arranged complementary to each other, so that one cylinder has an explosive mixture and the other a non-explosive mixture therein, and a sparking plug in each cylinder the said sparking plugs of each pair of complementary cylinders being arranged in series in the secondary circuit of each of said induction coils.
6. In a sparking system the combination with a mechanically operated contact device for opening and closing a circuit for a constant length of time irrespective of the speed at which said device may be operated, a distributer, a pair of electrical circuits alternately thrown into series with said contact device by said distributer, an induction coil in each of said circuits, of a pair of secondary circuits, one for each of said induction coils, a pair of sparking plugs arranged in series in each of said secondary circuits, and means to short circuit either end of the secondary windings of each of said coils to cut out the plug connected to that end of said coil.
7. The combination with an induction coil of a pair of cylinders arranged complementary to each other, a sparking plug in each cylinder and comprising an insulated and a grounded member, an electrical connection between said insulated members and the terminals of said coil, an electrical connection leading from the ground to a point adjacent the terminals of said coil and means to connect either end of said coil with said connection.
8. The combination with the secondary circuit of an induction coil, of a pair of cylinders arranged complementary to each other, a sparking plug in each cylinder and comprising an insulated and a grounded member, an electrical connection between each of said insulated members and a terminal of said coil, an electrical connection leading from the ground to a point adjacent each terminal and means to close the circuit through said ground and one of said sparking plugs.
9. The combination with a plurality of induction coils having primary and secondary windings, and each coil being provided with a vibrator to make and break the primary circuit, of a plurality of cylinders arranged in complementary pairs, a sparking plug comprising insulated and grounded members mounted in each cylinder, said insulated members of a pair of plugs arranged in complementary cylinders and arranged in series with the secondary winding of one coil, a contact device, a distributer having movable and stationary terminals, each stationary terminal being arranged in series with the primary windings of one of said coils, an electrical connection from said movable member to said contact device, an electrical connection from said contact de-

vice to the other terminal of the primary winding of each coil, a single condenser around said contact device and one of said vibrators, and means to operate said contact device and said movable terminal of the distributor synchronously, to produce a sparking impulse in each of the secondary circuits successively.

10. The combination with a sparking circuit comprising a primary circuit, an induction coil therein, and a secondary circuit connected to the secondary winding of said coil, of a pair of complementary cylinders, a sparking plug in each cylinder, each plug com-

prising an insulated and a grounded member, the insulated members of said plugs of a pair of cylinders being arranged in series in said secondary circuit, and manually operated means to ground either end of the secondary winding of said induction coil. 15 20

In witness whereof, I have hereunto set my hand this 20th day of December, A. D. 1906.
